UNITED STATES PATENT OFFICE.

JOHN C. ETTERS, OF CANTON, PENNSYLVANIA.

DESIGN FOR A BAG OR SACK HOLDER.

SPECIFICATION forming part of Design No. 29,676, dated November 15, 1898.

Application filed October 19, 1898. Serial No. 694,048. Term of patent 7 years.

To all whom it may concern:

Be it known that I, JOHN C. ETTERS, a citizen of the United States, residing at Canton, in the county of Bradford and State of Pennsylvania, have invented and produced a new and original Design for a Bag or Sack Holder, of which the following is a specification, reference being had to the accompanying drawing.

The drawing is a plan view of a bag or sack holder.

As shown in the drawing, the leading or material feature of my design consists of a

coil A, with arms B extending therefrom, with parts C, as shown.

Having described my invention, what I claim as new, and desire to secure by Letters Patent, is—

The design for a bag and sack holder, as herein shown and described.

JOHN C. ETTERS.
